[57] CLAIM

The ornamental design for a tamper evident closure, as shown and described.

DESCRIPTION

FIG. 1 is a perspective view of a tamper evident closure according to my design;

FIG. 2 is a perspective view of the closure portion of a tamper evident closure, shown at an enlarged scale, and shown without the ring portion for ease of illustration, and with a portion cut away to reveal an interior cross section; FIG. 3 is a perspective view of the ring portion of a tamper evident closure, shown at an enlarged scale, and shown without the closure portion for ease of illustration, and with a portion cut away to reveal interior elements and an interior cross section; it being understood that the interior side shown is a mirror image of that not shown; and,

FIG. 4 is a perspective view of a tamper evident closure, shown with a portion cut away to reveal interior elements and an interior cross section.
